UNITED STATES PATENT OFFICE.

OSCAR VILHELM BORGESON, OF BROOKLYN, NEW YORK, ASSIGNOR OF ONE-HALF TO
HERMAN SCHULTZ, OF BROOKLYN, NEW YORK.

AMUSEMENT DEVICE.

1,371,845.

Specification of Letters Patent. Patented Mar. 15, 1921.

Application filed March 18, 1920. Serial No. 366,825.

To all whom it may concern:

Be it known that I, OSCAR V. BORGESON, a citizen of the United States, and resident of the city of New York, borough of Brooklyn, in the county of Kings and State of New York, have invented a new and Improved Amusement Device, of which the following is a full, clear, and exact description.

10 This invention relates to amusement devices, toys, games or the like.

The principal object of the present invention is to provide an amusement device which is in the nature of a game requiring 15 a certain amount of skill and in which the element of luck plays only a secondary part, thus rendering the same highly amusing and interesting to the participants of the same.

20 Another object in view is to provide an amusement device which simulates a race course over which a plurality of racing bodies are adapted to be moved between a "starting point" and a "goal," each of said 25 bodies being under the direct control of one of the participants of the game, with mechanism provided which permits the participants to match their skill in avoiding penalties for a failure to observe certain 30 restrictions.

A further object of the invention is to provide a device of the character described which includes automatic means for returning 35 the racing bodies to the "starting point" after the winning body has reached the "goal."

A still further object of the invention is to provide a device of the character set forth 40 which includes means for automatically presenting the front of the bodies in the direction of travel in order to simulate more closely the real instrumentality which is represented.

Another object of the invention is to provide 45 an apparatus for carrying out the foregoing and other objects, which is simple in construction, inexpensive to manufacture and assemble and which is automatic in operation to high degree.

50 With these and other objects in view which will be more readily apparent as the nature, purpose and operation of the device is better understood from the following

description and claims, reference is had to the accompanying drawings forming a part 55 of this application and in which;

Figure 1 is a front elevation of the assembled device.

Fig. 2 is a sectional view therethrough with parts broken away to disclose the underlying structure.

Fig. 3 is a fragmentary plan view.

Fig. 4 is a sectional view therethrough taken approximately on the line 4-4 of 65 Fig. 3.

Fig. 5 is a detailed sectional view taken on the line 5-5 of Fig. 2.

Fig. 6 is a sectional view taken on the line 6-6 of Fig. 4.

Referring to the drawings by characters 70 of reference which denote like parts throughout the several views thereof, 10 designates a frame defining a stage 11 in front of which is positioned a counter 12. At opposite ends of the stage and supported by the 75

frame work are arranged the transverse beams 13 and 14 between which are suspended a plurality of parallel suspension cables 15 which constitute trolleys throughout the length of which are movable a plurality of carrier blocks 16 each of which is

designed to be supported by a pair of said 80 cables, said carrier blocks are being pro-

vided with tubular guides 17 through which the cables are passed in mounting the same 85

thereon. Racing bodies 18 here illustrated as miniature aeroplanes are swivelly supported from the carrier blocks by the pinion shafts 19 which pass through a central

aperture in the blocks and are provided 90 with pinions 20 keyed to the upper extre-

mity thereof which protrudes above the upper surface of said carrier blocks. A rack 95 bar 21 is longitudinally slidable on the upper surface of each carrier block in the guides 22 and the teeth of said rack bar

engage and co-act with the teeth of the pinion 20 for a purpose to be hereafter set forth. The opposite extremities of the rack 100

bar are provided with apertures for the re-

ception of the terminals of an endless drive belt 23 which is trained around the idler pulley 24 secured to the transverse beam 14 and around the drive pulley 25 arranged

adjacent the transverse beam 13.

105 The means for rotating each of the drive

pulleys 25 comprises the individual operating wheels 26 secured to the vertical shafts 27 which pass through the counter 12. Each of said shafts 27 is provided with a beveled gear 28 meshing with a similar gear 29 on the rearwardly extending shaft 30 which is provided at its opposite end with a bevel gear 31 meshing with a bevel gear 32 on the vertical shaft 33. The upper end 10 of the vertical shaft is provided with a cone friction clutch member 34 which normally engages the cone clutch member 35 upon which the drive pulley is mounted. A centrifugal speed governor 36 is provided in 15 the length of the shaft 33 adjacent the clutch member 34 in order to control the engagement of said clutch member with the clutch member 35. When the drive pulley is revolved in the direction indicated by the arrow in Fig. 3 the initial movement of the belt 23 will exert a pull on the rack bar 21 thereby moving the same through the guides until the toothed portion thereof engages the forward guide to arrest further movement 20 thereof. The engagement of its teeth with the pinion will serve to rotate said pinion and its shaft 19 in order to present the nose of the racing body simulating an aeroplane, in the direction of travel. Further rotation 25 of the drive pulley will advance the carrier toward the beam 14 which will be hereinafter termed the "goal."

Means for returning the carriers toward the beam 13 hereinafter termed the "starting point," is provided and said means includes the drums 37, each of which is mounted upon a transverse stationary shaft 38. A convolute spring 39 is secured at one extremity to the shaft 38 as at 40 and at its opposite extremity to the drum as at 41. A cable 42 is secured to the drum at one extremity and adapted to be wound thereon. The opposite extremity of said cable is attached to the rear end of the rack bar 21. When the carriers are advanced toward the "goal" the cables 42 will be unwound from the drum resulting in the winding up of the spring 39 on the shaft 38 and the placing of said drums under a tension.

50 In operation of the device each player selects one of the operating wheels 26 and turns the same in the proper direction to advance his plane or racing body 18. Should any one of the players seek to advance his plane above a pre-determined speed the centrifugal governor 36 will disengage the clutch member 34 from the clutch member 35. The drive pulley and clutch member 35 will then be free to move and immediately 55 the tension on the spring 39 will exert a pull on the cable 42 initially moving the rack bar 21 to the rear to present the nose of the plane toward the "starting point" and further resulting in the returning of the carriage 60 and plane to the "starting point" thus penal-

izing the player for his lack of skill in judging the maximum speed at which the plane will travel. The clutch member 35 is supported by a vertical shaft 43 mounted in the brackets 44 for vertical movement, a stop 70 45 being provided to limit the downward movement of the same.

Means is provided for returning all of the carriers to the "starting point" when the winning plane reaches the "goal" and said means includes a rock shaft 46 having a plurality of arms 47 keyed thereto for movement therewith, the free extremities of said arms being bifurcated or forked as at 48. Trunnions 49 are provided in the furcations of the bifurcated portion 48 and the same engage in the annular groove 50 formed in the sleeve 51 of the clutch member 35. A cam 52 is keyed to the rock shaft and provided with an offset lip 53 which is normally engaged by the offset portion 54 of the pivoted catch 55. An arm 56 is secured to the rock shaft 46 and a coiled contractile spring 57 is secured at one extremity to the free terminal of the arm 56 and at 90 its opposite extremity to the frame 10 whereby to normally exert a tension to rotate the shaft in the direction indicated by the arrow when the offset portion 54 of the catch 55 is disengaged from the offset portion 53 of the cam 52. The means for disengaging the offset portions 53 and 54 comprises a second rock shaft 58 mounted transversely in the frame adjacent the beam 14 and a depending arm 59 secured thereto and connected by the cable 60 to the catch 55. A plurality of triggers 61 are also secured to the rock shaft 58 and are each positioned between pairs of suspension cables 15 which support the respective carriers so that when the carrier block of the winning plane contacts with its trigger arm 61 the rock shaft 58 will be rotated to exert a pull on the cable 60 for disengaging the offset portion 54 from the offset portion 53 of the cam. The rock shaft 46 will be rotated under the action of the spring 57 thereby lifting the arms 47 and disengaging the clutch member 35 of each clutch from its respective clutch member 34 to permit all of the drums 37 to rotate under the action of their springs 39 whereby to return all of the carriages and planes to their "starting point" simultaneously. Means is provided for rotating the rock shaft 46 in the opposite direction to reset the mechanism and engage all of the upper clutch members 35 with the lower clutch members 34 simultaneously and at the same time dispose the offset portion 53 in engagement with the offset portion 54. The said means includes an arm 65 secured to the rock shaft 46 adjacent the front wall of the frame 10 defining the stage and a pivoted operating lever 66 connected thereto by means of a length of cable 67. 130

- While the racing bodies have been here illustrated as miniature aeroplanes, it is of course understood that such a showing is merely illustrative of one form of racing body which may be employed. It is also to be understood that the frame work, counter and stage may be dispensed with and any other arrangement or construction of a supporting frame substituted if desired.
- 10 While there has been illustrated and described a preferred form of apparatus, it is to be understood that variations and modifications which fall within the scope of the appended claims and which do not depart 15 from the spirit of the invention may be resorted to when found expedient.
- Having thus described my invention, what I claim as new and desire to secure by Letters Patent, is:—
- 20 1. In an amusement device, a race course having a starting point and a goal, a plurality of racing bodies adapted to be moved between the starting point and the goal, independently operable means for advancing 25 the bodies toward the goal, and means for returning each of said bodies to the starting point upon operation of its advancing means above a pre-determined speed, comprising a clutch, a centrifugal governor for controlling the same, a drum mounted adjacent the starting point, a cable connecting the racing body to the drum, and means for tensioning the drum upon movement of said body toward the goal.
- 30 2. In an amusement device, a race course having a starting point and a goal, a plurality of racing bodies adapted to be moved between the starting point and the goal, independently operable means for advancing 35 the bodies toward the goal comprising an endless belt having its ends connected to the body, an idler guide pulley adjacent the goal and a drive pulley adjacent the starting point over which said belt is trained, a driving mechanism for said belt, and means for returning each of said bodies to the starting point upon operation of its advancing means above a predetermined speed, said means comprising a clutch, a centrifugal governor for controlling the same, a drum mounted adjacent the starting point, a cable connected to the racing body and the drum, means for tensioning the drum upon movement of the body toward the goal, in combination with means operable by the swinging body upon its arrival at the goal for automatically rendering all of said returning means active 100 simultaneously, and means for initially presenting the front end of the bodies in the direction of travel.
- 35 5. In an amusement device simulating an aeroplane race, a frame having spaced transverse supporting beams and a plurality of parallel cables suspended therebetween to constitute a race course having a starting point and a goal, a plurality of racing bodies supported by and movable over said cables between the starting point and the goal, independently operable means for advancing the bodies toward the goal, and means for returning each of said bodies to the starting point upon operation of its advancing means beyond a pre-determined speed.
- 40 6. In an amusement device simulating an aeroplane race, a frame having spaced transverse supporting beams and a plurality of parallel cables suspended therebetween to constitute a race course having a starting point and a goal, a plurality of racing bodies supported by and movable over said cables between the starting point and the goal, independently operable means for advancing the bodies toward the goal, means for returning each of said bodies to the starting point upon operation of its advancing means beyond a pre-determined speed, and means 110
- 45 115
- 50 120
- 55 125
- 60 130
- 65
- starting point upon operation of its advancing means above a predetermined speed, said means comprising a clutch, a centrifugal governor for controlling the same, a drum mounted adjacent the starting point, a cable connected to the racing body and the drum, and means for tensioning the drum upon movement of the body toward the goal, in combination with means operable by the swinging body upon its arrival at the goal for automatically rendering all of said returning means active simultaneously.
4. In an amusement device, a race course having a starting point and a goal, a plurality of racing bodies adapted to be moved between the starting point and the goal, independently operable means for advancing the bodies toward the goal comprising an endless belt having its ends connected to the body, an idler guide pulley adjacent the goal and a drive pulley adjacent the starting point over which said belt is trained, a driving mechanism for said belt, means for returning each of said bodies to the starting point upon operation of its advancing means above a predetermined speed, said means comprising a clutch, a centrifugal governor for controlling the same, a drum mounted adjacent the starting point, a cable connected to the racing body and the drum, means for tensioning the drum upon movement of the body toward the goal, in combination with means operable by the swinging body upon its arrival at the goal for automatically rendering all of said returning means active simultaneously.

for rendering all of said returning means active simultaneously upon the arrival of the winning body at the goal.

7. In an amusement device simulating an aeroplane race, a frame having spaced transverse supporting beams and a plurality of parallel cables suspended therebetween to constitute a race course having a starting point and a goal, a plurality of racing bodies supported by and movable over said cables between the starting point and the goal, independently operable means for advancing the bodies toward the goal, means for returning each of said bodies to the starting point upon operation of its advancing means beyond a pre-determined speed, means for rendering all of said returning means active simultaneously upon the arrival of the winning body at the goal, and means for initially presenting the forward end of the bodies in the direction of travel of the same.
8. In an amusement device, a plurality of carriages, racing bodies carried thereby, an overhead suspension means for supporting said carriages, said suspension means defining a race course having a starting point and a goal between which the carriages are adapted to be moved, independently operable means for advancing the carriages toward the goal, means for returning each of said carriages to the starting point, and means for initially presenting the front end of the bodies in the direction of travel of its carriage, comprising a vertical shaft secured to each body and journaled in its carriage, a pinion on each shaft, a longitudinally shiftable rack engaging said pinion and having its opposite extremities respectively connected to the carriage advancing

means and the carriage returning means, and means respectively on the carriage and rack adapted to co-act for limiting the shaft of the rack.

9. In an amusement device, a race course having a starting point and a goal, a plurality of racing bodies adapted to be moved between the starting point and goal, independently operable means for advancing the bodies toward the goal comprising an endless belt having its ends connected to the bodies, an idler guide pulley adjacent the goal and a drive pulley adjacent the starting point over which said belt is trained, a driving mechanism for said belt, means for returning each of said bodies to the starting point upon operation of its advancing means above a predetermined speed comprising a clutch, a centrifugal governor for controlling the same, a drum mounted adjacent the starting point, a cable connecting the racing body and drum, means for tensioning the drum upon movement of the body toward the goal, and means for rendering all of said returning means active simultaneously upon the arrival of the winning body at the goal comprising a common shaft traversing all of said clutches, arms secured to said shaft and respectively engaged with one of the members at each clutch, means for rotating said shaft to cause the arms to disengage the clutch members, means for normally retaining said shaft against rotation, and means connected within said latter means and arranged adjacent the goal in the path of movement of the racing bodies for releasing said retaining means.

OSCAR VILHELM BORGESON.
